United States Patent

Des. 242,161

Patented Nov. 2, 1976

242,161

FLOWER POT OR THE LIKE

Ted Dziewulski, Bartlett, Ill., assignor to Phillips Petroleum Company, Bartlesville, Okla.

Filed Oct. 28, 1975, Ser. No. 625,809

Term of patent 14 years

Int. Cl. D11—02

U.S. Cl. D11—152

FIG. 1

FIG. 2

FIG. 3

FIG. 4

FIG. 1 is a front elevational view of a flower pot or the like, showing my new design; the opposite side being the same as the side shown herein;

FIG. 2 is a top plan view thereof;

FIG. 3 is a bottom plan view thereof; and

FIG. 4 is an elevational view in cross section taken along line 4-4 in FIG. 2.

I claim:

The ornamental design for a flower pot or the like, as shown and described.
